UNITED STATES PATENT OFFICE.

PERCIVAL S. TICE, OF CHICAGO, ILLINOIS.

AIR-WASHER FOR INTERNAL-COMBUSTION ENGINES.

1,379,062.

Specification of Letters Patent. Patented May 24, 1921.

Application filed August 25, 1919. Serial No. 319,602.

To all whom it may concern:

Be it known that I, PERCIVAL S. TICE, a citizen of the United States, residing at Chicago, in the county of Cook and the State of Illinois, have invented certain new and useful Improvements in Air-Washers for Internal-Combustion Engines, of which the following is a specification, reference being had to the accompanying drawings, forming a part thereof.

The purpose of this invention is to provide an improved means for washing the air for admixture with the liquid fuel for supplying an internal combustion engine, and simultaneously moistening the air for the advantage afforded by such moisture. It consists in the elements and features of construction shown and described, as indicated in the claims.

20 In the drawings:

Figure 1 is a trans-axial section of one chamber of a device embodying this invention.

25 Fig. 2 is an axial section of both chambers of the device.

Fig. 3 is an enlarged detail view, partly sectional, showing the water-delivery conduit from the water chamber to the air inlet conduit, section being made axially with respect 30 to the valve and its chamber which controls the water inlet, and the discharge or terminal member of the water conduit being partly broken away and shown in axial section with a line of discharge apertures.

35 Fig. 4 is a section at the line, 4—4, on Fig. 3.

The device shown in the drawings comprises a cylindrical body member, A, which is partitioned into two chambers by a trans-40 axial partition, B, the chamber, C, at one side of said partition being the water reservoir, the chamber, D, at the other side of said partition being a chamber in which the washing of the air takes place and in which 45 a partial vacuum is produced by its connection with the engine intake. E is the air inlet conduit which is a convolute duct mounted within the chamber, D, having its intake end registering with the aperture, d, 50 in the periphery of said chamber, D, with its delivery mouth situated at substantially the same level as said intake mouth, d, facing downwardly and provided with a coarse strainer, e. This air inlet conduit is con-55 volute in a vertical plane and is narrowed at the lowest point of its convolute course, as

seen at E¹, for confining the air current passing therethrough to a relatively thin body which may be traversed by the water shower delivered across the convolute passage by the 60 water connections which will now be described.

F is the water conduit which leads from the lower part of the water chamber, C, through the partition, B, into the air washing chamber, D, not so as to discharge therein except as hereinafter described, but extending into said chamber at a position which brings it into immediate contact with the upper side of the convolute air inlet 70 conduit, E, at the lower part of the convolute course thereof, at which, as above stated, said conduit is reduced in cross-section. The water duct, F, is designed to be lodged permanently upon the upper outer 75 surface of said convolute air inlet conduit, and the two parts have registering perforations, f, for discharge of the water from the water conduit pipe into the air inlet conduit, E, crosswise of the latter at its point of re- 80 duction in cross-section. The water conduit, F, has a branch, F², which extends into and is in open communication with the lower part of the chamber, D, over the center of the sediment pocket, H, with which 85 the chamber, D, is provided at the lower side. This sediment pocket is provided with a cap or closure, I, adapted to be screwed into it at the lower end, said cap carrying a cup, i, which protrudes up within the sediment pocket forming a substantial lining 90 thereof and really constituting the pocket itself in which the sediment accumulation is received so as to be removed with the cap or plug. 95

The water conduit pipe, F, is provided with a fitting F¹, at its inlet end, which is provided with a valve J, which seats upwardly, and which is held normally seated by a spring K, reacting against a stop k, on the 100 stem, and against the upper end of said fitting, F¹. The stem, L¹, extends up through the height of the chamber, C, having its upper end guided in a spider, L, mounted in the filling aperture, c, of the chamber, C, 105 which filling aperture is closed by an air-tight seating plug, C¹. The length of the stem is such that when the plug is screwed home for closing the chamber, C, air-tight, the valve, J, is pushed off its seat; but when 110 the chamber is opened by removal of the plug for filling, the valve is normally seated

by the spring, K, so that the water with which the chamber is filled does not flow through the water duct into the chamber, D, nor into the air-inlet conduit, E.

5 The detail construction of the valve, J, and its seat are shown in Fig. 3, being that the seat, f^1 , is conical, and the valve, J, is cylindrical for seating by its circumferential edge on the sloping conical seat about mid-way of the slope. A square retaining washer, J^1 , is provided below the valve, the diagonal of this washer being the diameter of the bore which terminates in the conical seat, f^1 , whereby guidance for the valve is afforded by the corners of the washer following this cylindrical bore, and required clearance for water is obtained at the segmental spaces between the square washer and the circumscribed cylindrical wall of the bore.

10 The operation of the device described is as follows: The reservoir C being filled with water through the filling aperture c, the plug C^1 is screwed in to seal the filling aperture.

15 As described, the screwing in of plug C^1 causes the valve J to be opened, thus communicating chamber C with chamber D and the air conduit E by way of the water conduits F and F^2 and the apertures f. It fol-

20 lows that water will flow from chamber C, past valve J and through water conduit passages F and F^2 into chamber D by virtue of the head of water in C. This withdrawal of water from reservoir C reduces the pressure

25 within that reservoir by an amount equal to the head of water in C above the small ports f. When the pressure in C is reduced by this amount, the flow of water from C into D becomes intermittent, being periodically inter-

30 rupted by a counter flow of air from conduit E through water passages f, F^2 and F and past valve J to satisfy partially the subatmospheric pressure existing in reservoir C. This intermittent flow continues until the water

35 level in D, and therefore in passage F^2 , has risen to submerge the passage F and therefore the small passages f, thus providing a water-seal and preventing further entrance of air to reduce the partial vacuum in C.

40 The arrangement of water passages and chambers shown constitutes a constant level control on the height of water in chamber D, water being admitted from C only when the level in D has fallen to uncover the small apertures f in water conduit F, at which

45 time air percolates past valve J and bubbles up through the water in C raising the pressure in reservoir C and permitting a further discharge of water into chamber D. It will

50 be understood that when apertures f are water sealed as above, the lower portion of air conduit E will contain water to the level of the apertures f.

55 The chamber D of the device being connected with the air intake passage of the

engine, as indicated by the coupling member N, partly shown in Fig. 1, the air passing to the engine is constrained to enter the device at d, pass through the air conduit E—E, and discharge into chamber D, from 70 which the engine draws its supply.

It is understood that when a fluid, as air, flows through a conduit of varying cross-sectional area, the pressures existing in the fluid at various points along its line of flow 75 are directly as the cross sectional areas of the conduit at those points. From this it follows that the pressure at E^1 , the narrowest portion of the air conduit E, is at all times materially less than that existing at 80 either end of the conduit E, or in chamber D.

Since the lower end of the water passage F² is in open communication with chamber D, and its other end, represented by the apertures f, is open to the constricted portion 85 E^1 of the air conduit E, which is a region of lower pressure, the flow of air will cause a discharge of water from apertures f across the air stream at E^1 . By virtue of the velocity of the air flow through 90 E^1 , the water discharged from apertures f is more or less finely divided or sprayed and is carried on by the air and is discharged with it into the chamber D. From the point 95 E^1 to the exit e of air conduit E, the air and water are forced into very intimate contact, to the end that dust and all solid matter in entrainment in the air may be wetted and absorbed by the water, thus washing the air and freeing it of this material before it enters the engine.

By virtue of the direction of discharge from conduit E and by virtue of the low air velocities in chamber D, the water carried by the air stream from the aperture f 105 is returned to the chamber D, with the exception of that portion which is evaporated and passes out with the air as a vapor content. Thus the circulation path of the water is complete from chamber D, by way of 110 water passage F^2 and apertures f, to air conduit E, and back to chamber D. The water in the lower portion of chamber D is thus recirculated, carrying with it the dust removed from the air, until its volume 115 has been reduced by evaporation sufficiently to break the water seal initially established at the apertures f. When this occurs water again flows from chamber C to reestablish the sealing of apertures f, at the same time 120 replenishing the water supply in D, to maintain the discharge of water from apertures f into air conduit E.

The dust originally in the air entering the device, being absorbed by the water, appears as sediment in the latter, and settles into the cup i from which it is removed by withdrawal of the cap I. It will be understood, of course, that the chamber C will require to be resupplied with water, from 130

time to time, to insure that a supply of water be available for the purpose of maintaining a suitable level of water in chamber D.

5 I claim:

1. An air washing and moistening device for internal combustion engines comprising a washing chamber, an air inlet conduit extending within and discharging in said 10 washing chamber with a duct for discharging a water spray across the path of the air flowing through the air inlet; the course of the air inlet conduit being downward from its intake to a low point and thence upward 15 to its discharge mouth whereby there is formed a water trap at said low point, and the water spray discharge being positioned for discharging at the low point of the air inlet conduit.
2. An air washing and moistening device for internal combustion engines comprising a water supply chamber, a washing chamber; an air conduit within the washing 25 chamber, opening at one end for air discharge at a relatively high point therein, and at the other end for air inlet from without said washing chamber; a conduit for water from the water supply chamber, having its intake at a relatively low level in 30 said water supply chamber, discharging into the air conduit at a point near the lowest part of the course of said conduit; the water conduit being constructed for being closed

air-tight, except as to water discharge through said conduit. 35

3. In a construction defined in claim 2, a valve controlling the intake of the water conduit in the water supply chamber; means by which said valve is normally closed and a stem by which it may be opened against 40 the closing means; said chamber having a filling mouth and a closure therefor which encounters the valve stem when adjusted into closing position, for opening the valve in the movement for closing the chamber. 45

4. In a structure defined in claim 2, the air conduit being deflected from a straight course in a vertical plane, having its delivery mouth facing downwardly and narrowed in cross-section at the low point in 50 its course at which the water conduit discharges into it.

5. In a construction defined in claim 2, the water conduit having a branch which discharges directly into the washing chamber at the lower part thereof below the low point of the air conduit, and thereby is adapted for intake of water through said washing chamber into said water conduit when the water accumulates in said washing 60 chamber above the level of discharge from the water conduit into the air conduit. 55

In testimony whereof, I have hereunto set my hand at Chicago, Illinois, this 21st day of August, 1919.

PERCIVAL S. TICE.
